(57) CLAIM

The ornamental design for a golf tee, as shown and described.

DESCRIPTION

FIG. 1 is a top-front perspective view of a golf tee showing my new design;

FIG. 2 is a bottom perspective view thereof;

FIG. 3 is a front side view thereof;

FIG. 4 is a back side view thereof;

FIG. 5 is a right side view thereof;

FIG. 6 is a left side view thereof;

FIG. 7 is a top plan view thereof;

FIG. 8 is a bottom plan view thereof;

FIG. 9 is a perspective view of the golf tee, shown without unclaimed subject matter;

FIG. 10 is a right side view thereof; and,

FIG. 11 is a left side view thereof.

The broken lines in the drawings depict environment and form no part of the claimed design.
